ATTORNEYS

UNITED STATES PATENT OFFICE.

GEORGE YATES, OF CLEVELAND, OHIO.

TRACTION-MOTOR.

1,374,708.

Specification of Letters Patent.

Patented Apr. 12, 1921.

Application filed March 27, 1920. Serial No. 369,227.

To all whom it may concern:

Be it known that I, GEORGE YATES, a citizen of the United States, and a resident of Cleveland, in the county of Cuyahoga and 5 State of Ohio, have invented certain new and useful Improvements in Traction-Motors, of which the following is a specification.

My invention is an improvement in traction motors, and relates more particularly to the rotating armature type.

An important object of my invention is to provide a traction motor in which the effective driving power will be transmitted 15 directly to the car wheels, thereby eliminating the use of transmission gearing, and increasing its efficiency.

Another important object is to provide a traction motor which may be easily inspected and cleaned.

Another object is to provide an apparatus of the above named character which will be simple in construction and comparatively inexpensive to manufacture.

25 Other objects will become apparent during the course of the following description.

In the drawings forming a part of this specification and in which like numerals are employed to designate like parts throughout the same,

Figure 1 is an elevation partly in section of the motor embodying my invention,

Fig. 2 is a vertical section on the line 2-2 of Fig. 1, showing the bearings, and

35 Fig. 3 is a vertical section on the line 3-3 of Fig. 1, showing the commutator and brushes.

In the drawings, the car wheels 5 and 6 are mounted upon a cylindrical casing 7 at 40 its opposite ends. The wheels 5 and 6 are secured against outward displacement by the face plates 8 and 9 which are bolted to the casing 7 and revolve with it.

Within the casing 9 is secured an outer 45 bearing track 10 and an inner track 11 adapted to accommodate roller bearings 12.

A similar construction (not shown) is provided at the opposite end of and within the casing 7. The roller bearings 12 are separated by a ring 13 and are held against lateral movement by the face plate 9 and a web 14.

55 A commutator 15 is mounted within the casing 7 and is attached thereto by any suitable means. Also mounted within the casing 7 is an armature 16 which is con-

nected with the commutator in the usual manner.

For convenience of cleaning or inspection, handholes 17 are provided. These 60 handholes may be located in a suitable place, such as directly over each brush. It will be noticed that so far I have confined my description to the rotating part of my invention. The axle 18, which is stationary, is provided with a supporting ring of insulating material 19 upon which are mounted the brushes 20. Set screws 21 serve to clamp brushes 20. The inner walls of the hollow axle 18 are provided with 65 contact blocks A and B insulated from the axle by any suitable insulating material C. The field magnets 22 are mounted upon the axle 18 as shown in Fig. 1. Current is supplied through the end of the axle and conveyed to the brushes and field through 70 wires 23 and 24 housed within the axle 18.

In use, current is supplied through the end of axle 18 to the brushes 20 and field 75 22. Due to the magnetic flux set up in the field and the current in the armature coils, the armature 16 will revolve, moving with it the casing 7 and wheels 5 and 6. It will be noticed that the full turning effort is transmitted directly to the wheels, thus 80 eliminating much loss due to the use of gearing or other power transmission mechanism.

It is to be understood that various changes 90 in the size, shape and arrangement of parts may be resorted to without departing from the spirit of the invention or the scope of the subjoined claims.

I claim:

1. A traction motor, consisting of a cylindrical wheel carrying casing, a shaft within the casing, antifriction bearing between the casing and the axle, a motor armature secured to the casing, a commutator also secured to the casing, and brushes carried by 95 the axle and delivering electric current to the commutator.

2. A traction motor comprising a cylindrical casing, a pair of tractor wheels mounted upon the casing and adapted to 100 revolve with the casing, a motor armature secured to the casing, a commutator secured to said casing, and stationary brushes mounted upon an axle to deliver electric current to the commutator.

3. The combination of a stationary axle, 105 field magnets and brushes mounted inter-

mediate the ends of said axle, a cylindrical casing, an armature and commutator carried by the casing, and a pair of wheels mounted one upon each extremity of said casing and adapted to revolve with the casing.

4. The combination of an axle, a field and brushes carried by the axle, a pair of wheels rotatably mounted on the axle, an armature and commutator, and supporting means for said armature and commutator, said supporting means being rigidly secured to each of the wheels and adapted to rotate with the wheels.
5. In an electric motor, a hollow shaft, field magnets and brushes carried by said shaft, electrical conductors carried within the axle to deliver electric current to the

brushes, an outer body portion rotatably mounted upon the axle, an armature and commutator carried by the outer body portion, and wheel rims mounted upon the extremities of the body portion.

6. In a traction motor, a hollow axle, a plurality of contact blocks mounted within the axle for protection and insulated therefrom, and means for delivering an electric current from the blocks to the motor.

7. In a traction motor, an axle, a wheel carrying casing, a face plate secured to each end of the casing, similar plates within the casing and in close proximity to each end plate, and antifriction bearings mounted between said plates and end plates.

GEORGE YATES.
